CABINET

Robert G. Mager, Ann Arbor, Mich., assignor to Robert Mager Associates, Inc., Ann Arbor, Mich.

Continuation of design applications Ser. Nos. 67,575 and 67,576, Nov. 17, 1961. This application July 9, 1963, Ser. No. 75,760

Term of patent 14 years

(Cl. D33—19)

FIGURE 1 is a perspective view of a cabinet showing my new design wherein the upper front panel member is two drawers;

FIGURE 2 is a left side elevational view of the cabinet shown in FIGURE 1;

FIGURE 3 is a right side elevational view of the cabinet shown in FIGURE 1;

FIGURE 4 is a perspective view of the cabinet design of FIGURE 1, wherein the upper front panel member is plain;

FIGURE 5 is a left side elevational view of the cabinet shown in FIGURE 4; and

FIGURE 6 is a right side elevational view of the cabinet shown in FIGURE 4.

This is a continuation of my application Serial No. D-67,575, filed November 17, 1961 and application Serial No. D-67,576, filed November 17, 1961, both now abandoned.

The essential feature of my design resides in the portions shown in solid lines and primarily in the forwardly extending cabinet door members having piano hinges in outer corners and underlying an overhanging upper panel, substantially as shown.

I claim:

The ornamental design for a cabinet, substantially as shown and described.
